(57) **CLAIM**

The ornamental design for an impression coping for dental implant prosthetic, as shown and described.

DESCRIPTION

FIG. 1 is a perspective view of an impression coping for dental implant prosthetic showing our new design;

FIG. 2 is a right side elevational view thereof;

FIG. 3 is a rear elevational view thereof;

FIG. 4 is a front plan view thereof;

FIG. 5 is a left side elevational view thereof;

FIG. 6 is a top plan view thereof;

FIG. 7 is a bottom plan view thereof;

FIG. 8 is a perspective view of a second variant of an impression coping for dental implant prosthetic showing our new design;

FIG. 9 is a rear plan view thereof;

FIG. 10 is a left side elevational view thereof;

FIG. 11 is a right side elevational view thereof;

FIG. 12 is a front elevational view thereof;

FIG. 13 is a top plan view thereof;

FIG. 14 is a bottom plan view thereof;

FIG. 15 is a perspective view of a third variant of an impression coping for dental implant prosthetic showing our new design;

FIG. 16 is a rear plan view thereof;

FIG. 17 is a right side elevational view thereof;

FIG. 18 is a left side elevational view thereof;

FIG. 19 is a front elevational view thereof;

FIG. 20 is a top plan view thereof; and,

FIG. 21 is a bottom plan view thereof.
